Primary Examiner — Richard Kearney*Assistant Examiner* — Melvin L Davis(74) *Attorney, Agent, or Firm* — Andrus Intellectual Property Law, LLP(57) **CLAIM**

The ornamental design for a face mask as shown and described.

DESCRIPTION

FIG. 1 is a top left perspective view of a face mask;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line showing of the face mask is for the purpose of illustrating portions of the article that forms no part of the claimed design.
